UNITED STATES PATENT OFFICE.

WILLIAM GEORGE BEATTY, OF FERGUS, ONTARIO, CANADA.

CARRIER.

1,367,653.

Specification of Letters Patent.

Patented Feb. 8, 1921.

Application filed April 1, 1920. Serial No. 370,421.

To all whom it may concern:

Be it known that I, WILLIAM GEORGE BEATTY, a British subject, and resident of the town of Fergus, in the county of Wellington and Province of Ontario, Dominion of Canada, have invented certain new and useful Improvements in Carriers; and I hereby declare that the following is a full, clear, and exact description of the same.

10 This invention relates to a carrier of that type in which the load is lifted by a hoisting pulley attached at one end to a rock shaft, on which is mounted a lock adapted to engage a stop block secured to the trackway, 15 and the other end of which is adapted to pass over a hoisting pulley and between a pair of rope gripping jaws, which open and close in parallel planes, one of the objects of the invention being to provide an adjustable 20 connection between the lock and the jaws to accurately adjust them to the diameter of the rope passing between them.

A further object of the invention is to provide a swiveled connection for the hoisting 25 pulley which will enable it to automatically adapt itself to the direction of the hoisting rope from the load to the hoisting pulley, and to provide an idler to maintain the alinement of the rope from the hoisting 30 pulley to the jaws.

A still further object of the invention is to provide the carrier with a detent to prevent the lock oscillating to close the jaws during the hoisting of the load and with a trip to 35 release the detent for the oscillation of the lock to close the jaws when the load is hoisted to its elevated position.

For an understanding of the invention reference is to be had to the following 40 description and accompanying drawings, in which:

Figure 1, is a side elevational view of the carrier with the parts positioned for the hoisting of the load,

45 Fig. 2, is an end view of the same.

Fig. 3, is a view similar to Fig. 1 looking at the carrier from the opposite side,

Fig. 4, is a top plan view of the carrier,

Fig. 5, is a longitudinal section of the carrier with the parts shown in Fig. 1, and

50 Fig. 6, is a similar view to Fig. 5 with the rope gripping jaws closed.

Like characters of reference refer to like parts throughout the specification and 55 drawings.

The operating parts of the carrier are

mounted in a frame *a*, connected by a swivel *b* to the car *c*, the wheels, *d*, of which are adapted to travel on the track rail *e*, on the under side of which is a stop block *f*. The 60 general principle of the construction of these parts is embodied in carriers commonly used in barn equipment.

Between the sides of the frame *a*, near the top at one end thereof, is journaled a rock 65 shaft *g*, on which is mounted a lock *h* adapted to engage with the stop block *f*, when the car comes into position with it for the hoisting of the load, and mounted in the frame *a* adjacent to the lock *h* is a pin *i*, on which 70 is mounted a rocking detent *j*.

The detent *j* is preferably of a U-shape, and its forks *j'* are adapted to engage the lock *h* and hold it in a set position to maintain the rope gripping jaws opened for the 75 movement of the hoisting rope during the lifting of the load.

Extending outwardly from the detent *j* is an arm *j''*, to which is attached a trip rope *j'''*.

Fulcrumed to the frame *a* is a trip lever 80 *k*, and pivoted to the lever *k* between its fulcrum and its free end are two arms *l*, which are pivotally connected at or near their upper ends with the arms *j'* of the detent *j*.

Passing through the frame *a* at the opposite end to the rock shaft *g* is a bolt *m*, and in front of the bolt *m* is a second bolt *m'*, which passes through the frame *a* in the same plane as the bolt *m*. Suspended from 90 the bolts *m*, *m'*, are two sets of links *o*, *o'*, and each of the links *o*, *o'*, has two sets of eyes *p*, *p'*, in oblique alinement to receive the pintles *q*, *q'*, of the rope gripping jaws *r*, *r'*, respectively, which owing to this construction open and close in parallel planes. Pivotally connected to the links *o* is a U-shaped coupling member *s*, having an axial bore *s'* through its head *s''*, for a draw bar *t*.

One extremity *t'* of the draw bar is of a 100 hook-shaped formation and engages in an eye *h'* in the lock *h*, and the other extremity *t''* is screw threaded and extends through the bore *s'*.

The screw threaded extremity *t''* of the 105 draw bar is provided with adjusting nuts *u*, *u'*, arranged on opposite sides of the head *s''* to adjust the jaws to the size of the rope used for the hoisting purpose. For example the nuts can be positioned to adjust the jaws 110 to close tightly against a hoisting rope of the smallest size, or they can be adjusted to close

tightly against a rope of the largest size, or they can be adjusted to close tightly against a rope of any diameter intermediate the largest and smallest sizes.

5 To enable the hoisting pulley to automatically adapt itself to the direction of the hoisting rope and its entrance to the jaws, the housing v of the hoisting pulley v' is provided with a sleeve v'' through which passes a bolt or pin w mounted in the frame a .

This swiveled arrangement for the hoisting pulley enables it to automatically adapt itself to the direction of the hoisting rope, which direction constantly varies according 15 to the size of the loads which it lifts. Interposed between the hoisting pulley and the rope gripping jaws is an idler x , journaled in the frame a , and arranged transversely to the hoisting pulley with its grooved perimeter substantially in the same plane as the top of the hoisting pulley and the ropeway 20 between the jaws.

Fixed on the rock shaft g on the opposite side of the frame a to the hoisting pulley v' 25 is an arm y , having a pivoted eye y' , to which the fixed end of the hoisting rope is attached.

As shown in the drawings the hoisting rope extends from the arm y to the hoisting 30 pulley v' , and passes between the rope gripping jaws r, r' . When the hoisting rope elevates the sling pulleys z , to engage with the tripping lever h , the latter releases the 35 detent j from engagement with the lock, which then oscillates with the rock shaft and closes the rope gripping jaws against the rope, the rock shaft being rotated by the weight of the load on the arm y , from the 40 position shown in Fig. 5 to that shown in Fig. 6. The rope gripping jaws and their related parts including the stop lock h remain in the position shown in Fig. 6 until they are again restored to the position shown in Fig. 5, by the lock h coming into engagement 45 with the stop block f on the return of the carrier to the hoisting position.

When the rope gripping jaws are closed against the hoisting rope the movement of the latter in the lowering direction is prevented and the carrier can then convey the 50 load to where it is to be dumped. On the return of the carrier to the hoisting position its momentum brings the lock h into forcible engagement with the stop block f , and the 55 latter then upsets the lock h from the position shown in Fig. 6 to that shown in Fig.

5, the rock shaft being at that time relieved of the weight of the load. The upsetting of the lock h actuates its related parts to reopen the rope gripping jaws, and the hoisting 60 rope can then descend for the next load.

Having thus fully described my invention, what I claim as new and desire to secure by Letters Patent is:

1. A carrier including an oscillating lock, 65 a pair of rope gripping jaws which open and close in parallel planes, and an adjustable connection between the lock and the jaws to regulate their movement to the diameter of the rope passing through them. 70

2. A carrier comprising a pair of rope gripping jaws which open and close in parallel planes, a rock shaft, an oscillating lock mounted on the rock shaft and connected with the jaws to open and close them, and a 75 swiveled hoisting pulley to automatically adapt itself with relation to the direction of the hoisting rope from its connection with the rock shaft to the entrance of said jaws.

3. A carrier comprising a pair of rope 80 gripping jaws which open and close in parallel planes, a rock shaft, an oscillating lock mounted on the rock shaft and connected with the jaws to open and close them, a swiveled hoisting pulley to automatically 85 adapt itself with relation to the direction of the hoisting rope from its connection with the rock shaft to the entrance of said jaws, and an idler interposed between the jaws and the hoisting pulley to maintain the 90 alignment of the rope.

4. A carrier including a pair of rope gripping jaws, an oscillating lock connected with the jaws to open and close them, a detent holding the lock and jaws in an open position, and a lever, pivoted to the carrier and connected with the detent, engaged by the 95 load when raised to automatically release the detent from the lock for the closing movement of the jaws. 100

5. A carrier including a rock shaft, a lock fixed thereon, a pair of rope gripping jaws connected with the lock and opened and closed by it as it moves with the rock shaft, a bifurcated detent to hold the lock and 105 jaws in open position, and an arm for actuating the detent to release it from the lock.

Fergus, Ontario, February 24th, 1920.

WILLIAM GEORGE BEATTY.
